Primary Examiner — Kevin K Rudzinski*Assistant Examiner* — Clare Ann Gannon(74) *Attorney, Agent, or Firm* — Wood Herron & Evans LLP(57) **CLAIM**

An ornamental design for a chair mat, as shown and described.

DESCRIPTION

FIG. 1 is a perspective view of a chair mat according to this invention; and,

FIG. 2 is a top view thereof.

The dashed lines depict portions of the chair mat that form no part of the claimed design.
